UNITED STATES PATENT OFFICE.

OSCAR E. WORMAN, OF MINNEAPOLIS, MINNESOTA.

ARTIFICIAL LIMB.

1,343,297.

Specification of Letters Patent. Patented June 15, 1920.

Application filed October 21, 1918. Serial No. 258,964.

To all whom it may concern:

Be it known that I, OSCAR E. WORMAN, a citizen of the United States, residing at Minneapolis, in the county of Hennepin and 5 State of Minnesota, have invented certain new and useful Improvements in Artificial Limbs, of which the following is a specification.

My invention relates to artificial limbs 10 and more particularly to artificial members for use in cases of amputation above the knee, although some of the features may also be used in other cases.

An object of my invention is to provide an 15 artificial member which will not only resemble the corresponding human member in appearance, but will function in a manner similar thereto, so that persons who have been crippled by the loss of certain limbs 20 may have their usefulness restored, while at the same time the handicap in appearance is overcome. Another object is to provide an artificial limb which will be easy to manufacture and which will insure the greatest 25 degree of comfort to the wearer.

The full objects and advantages of my invention will appear in connection with the 30 detailed description thereof and the novel features embodied in my inventive idea are particularly pointed out in the claims.

Referring to the accompanying drawings which illustrate my invention embodied in an artificial limb intended for use particularly in cases of amputation above the 35 knee,—

Figure 1 is a side view of connected lower and upper leg members partly broken away, as shown respectively at X and Y. Fig. 2 is a view of the knee joint showing a particular construction of tension device for the 40 knee joint. Fig. 3 is a view in perspective of the cam adjusting device used in the form of invention shown in Fig. 2. Fig. 4 is a view in cross section showing a construction 45 of joint which may be used for the shell members of artificial limbs. Fig. 5 is a view in cross section showing another form of joint for the shell members. Fig. 6 is a detail view showing means for connecting 50 suspenders with the thigh member. Fig. 7 is a detail view showing modified means for connecting suspenders with the thigh member. Fig. 8 is a rear view of a preferred 55 construction of the shank member. Fig. 9 is a side view of the shank member shown in Fig. 8. Fig. 10 is a cross sectional view of

the shank member. Fig. 11 is a sectional view showing an ankle joint construction. Fig. 12 is a sectional view showing another form of ankle joint construction. 60

Referring to the particular construction shown in the drawings which illustrate the principles of my invention and which may be varied in regard to mechanical details without departing from the spirit of the invention, 14 designates a shank member having a foot member 16 pivotally connected to the lower end thereof by means of an ankle bolt or cylinder 17. The shank member is pivotally connected by a knee joint with a 70 thigh member 18 which constitutes a solid socket limb portion to receive the stump of the wearer in cases of amputation above the knee. The shank member extends up to the knee joint and in order to form the attachment thereto, the shank member is provided on each side with knee joint straps 20 which are attached preferably on the inside thereof by means of rivets, nails, screws or other suitable fasteners 22. In a manner similar 75 to the construction disclosed in my co-pending application, filed on the same date here-with, the knee joint straps may, if desired, be provided with projections or offsets to rest upon the top edge of the shank member 80 and said top edge may, if desired, be provided with a notch or groove for receiving the projections or offsets. The upper ends of the knee-joint straps are provided with a cylinder or bushing 24 extending horizontally through openings in the straps from 85 one side to the other, with the intermediate portion connected to the thigh member in such manner as to permit bending of the knee joint to any desired position similar to 90 the action of the natural knee. The connection with the thigh member is preferably made by passing the cylinder 24 through an opening extending horizontally through a knee block 26 located at the lower end of the 95 thigh member. The knee block gives form and shape to the knee portion of the artificial limb and may be constructed of fiber, wood, leather, metal or any other substantial material or any combination thereof suitable 100 for shaping or molding into the form of a knee. The knee block may be continuous with the thigh member and form an integral part thereof, but is preferably constructed as a separate part which is secured in the 105 lower end of the thigh member in any suitable manner, as by rivets, nails, screws, or

110

other suitable fasteners, or by means of adhesive material such as glue. The hole through the knee block in which the cylinder 24 works may, if desired, be reinforced by a 5 bushing of leather, fiber, metal, or other suitable material for the purpose of making the limb more durable and practical for wear. The cylinder 24 may be supported or reinforced by a bar 28 attached to and extending from the shank and having its upper end surrounding the central portion of the cylinder. The bar 28 is made from metal or other durable material and by its engagement with the knee block serves as a check or stop for stopping the shank when the latter swings into a vertical or the desired position in alinement with the thigh member.

The shank member in cases of amputation above the knee may be thrown automatically forward by means of a spring, rubber, or other suitable elastic material so attached to the knee block and the rear of the shank that when the knee is bent 20 the elastic material will be stretched and the shank when free to move, will be caused to swing back into its straight position without effort of the wearer. The elastic member is attached to the shank at such a point below the knee block as will permit of a gradual and increased tension as the knee is bent either for a walking position or a sitting position of the wearer which makes it possible for the shank member to swing 25 readily and easily back into vertical position with the tension decreasing gradually until the shank comes to a dead center in its straight position. The principle involved in this construction is that when the limb stands in a vertical position, there is little 30 or no tension on the elastic member, while the tension gradually increases in proportion as the limb becomes bent for a walking or sitting position, the maximum tension being obtained when the limb is bent backward as far as it will go. Upon releasing 35 the foot from the ground the elastic member automatically brings the shank into a vertical position with the shank and thigh members in alinement with each other. No special effort is required for starting the bending of the knee and the movement is easy and natural. A convenient form of the device just described is illustrated in 40 Fig. 1 which shows an elastic strip 30 attached at its upper end to the knee block by means of a ring or fastener 32. The lower end of the strip is attached to an eye or fastener 34 mounted on a bar which 45 is pivoted at one end to the rear of the shank at a suitable distance from the top thereof. The other end of the bar 36 is provided with a screw threaded hole adapted to receive the screw threaded end of a 50 bolt 38 which extends through the shank

with its head 40 on the outside thereof, the parts being so provisioned that the screw threads of the bolt coöperate with the screw threads in the bar. The head 40 is provided with a notch or angular portion 70 by means of which the bolt may be turned to adjust the tension of the elastic strip.

Referring to Fig. 2 which shows another construction of the elastic member, a coil spring 42 is attached at its upper end to 75 the knee block 26 and at its lower end to an eye 44 or fastener in the upper end of the bar 46 which is provided with a slot 48 through which extend the bolts 50 which serve to attach the bar 46 slidably to the 80 inside of the shank member. The lower end of the sliding bar 46 is provided with a lug 52 which engages the periphery of a cam 54 secured to the inner end of a smooth bolt 56 which passes through an 85 opening in the shank in frictional engagement therewith and has a notched or angular head 58 by which the cam may be readily turned. The spring 42 holds the lug up into engagement with the cam, so that by turning 90 the latter the tension of the spring may be adjusted. In order to hold the cam 54 securely in its adjusted position, the lug 52 has a leaf spring 59 secured thereto and the upper end of this spring is provided with 95 a projection or raised portion 61 adapted to engage in any one of a series of recesses or notches 63 with which the periphery of the cam is provided. The cam may be readily turned for adjusting purposes, yet it 100 will be held sufficiently by the means just described so as to prevent it from being jarred out of its adjusted position.

The thigh member 18 may be constructed of fiber, rubber, leather, or any other suitable material which can be shaped or molded for forming a socket to receive the stump of the wearer. Both the thigh member and the shank member are preferably formed as shells by shaping sheets of 110 the proper material into the desired form and bringing the longitudinal edges together in such manner as to form an overlapping joint. Fig. 4 shows the joint formed by overlapping the longitudinal edges, the 115 outer portions of which are beveled at 60 so as to form a smooth surface both inside and outside. The joint is preferably reinforced by a strip 62 of substantial material fastened thereto on the inside by rivets, 120 nails, screws or by glueing. Fig. 5 shows the joint formed by providing one of the longitudinal edges with an offset portion 64 upon which the other longitudinal edge is 125 adapted to fit. The joint is preferably reinforced by a strip 66 of substantial material fastened to the inside by rivets, nails, screws or by glueing. In the case of the shank member, one portion thereof may be constructed with the offset joint shown in 130

Fig. 5 while the other portion may be constructed with the overlapping joint shown in Fig. 4. Since the reinforcing strips 62 and 66 have a breaking characteristic which is different from that of the shell, the limb is greatly strengthened and liability of the bolts 38 and 56 tearing loose from the fiber shell is avoided. The thigh member is preferably lined with leather or other suitable material, or, if desired, may be padded with felt or other suitable material for the purpose of shaping the socket and making it more comfortable for receiving the stump of the wearer. The padding material may be covered with leather or other suitable material for the purpose of making it more durable and to give the proper finish.

The shank member may, if desired, be controlled and brought forward by means of a suspender 68 consisting of leather, textile or elastic material or any other suitable material or combination thereof passing over the shoulder or over a belt around the waist of the wearer or by being fastened to the thigh member of the limb, the attachment to the respective parts being such that when the knee is bent, the shank can be either pulled into the position voluntarily by the wearer or is brought into position by means of an elastic member having its upper end fastened to the parts mentioned, the lower end being fastened preferably by means of a strip of leather, fabric or other suitable material which has its lower end secured to the shank member by rivets, screws, buttons or other suitable fasteners.

The thigh member which contains the stump of the wearer may be held up to the body by means of a pair of suspenders consisting of leather, textile or elastic material or any other suitable material or combination thereof going up over the shoulder and having the lower portions secured in suitable manner to the thigh member. As shown in Fig. 1, the rear lower portions 70 and 72 of the suspenders are attached to the upper back part of the thigh member and the two front lower portions are attached to the upper front part of the thigh member in suitable manner as by means of buckles 74 and 76 provided at said part of the thigh member. These attachments are made in such manner as will best serve the purpose of securely holding the limb to the body in the right position. As shown in Fig. 6 which illustrates the front upper portion of the right thigh member, the suspenders constructed of the material previously described may have their lower ends attached to a cord, such as the cord 80, consisting of leather, rubber, textile material or any other suitable material or combination thereof and so positioned that any tension or drawing caused by a bending or sitting position of the wearer is equalized by the cord work-

ing back and forth through pulleys and loops or any suitable combination thereof. As shown particularly in this figure, the thigh is provided with two buttons or other fasteners 78 located at each side of the front upper portion, there also being two buttons similarly located at each side of the rear upper portion. The cord 80 passes under a pulley mounted in a bracket 82 secured to the outer or right portion of the thigh member. The front portion of the cord passes through a loop 81 attached to the thigh member adjacent the pulley and the free end of the cord is provided with an eye 84 or other suitable member having an opening adapted to be placed over the front inner button 78. The rear portion of the cord passes in the same manner from the pulley through a loop corresponding to the loop 81 and has its free end fastened over a rear inner button or other fastener corresponding to the front button previously referred to. The four lower ends 86 of the suspenders are preferably provided with holes 88 and are connected to the cord 80 by means of curved members 90 over which the cord is adapted to slide. The two front lower ends 86 may be connected to the main portion of the suspenders by means of buckles 92. On account of the provision of four of the buttons or fasteners 78, it is obvious that when desired, the four suspender ends may be attached direct by means of the holes 88 to the four buttons or fasteners 78. This may be readily done in case of the breaking or pulling apart of any of the members which serve to connect the lower ends 86 to the thigh member. When the attachment is made in this manner, it closely resembles the attachment shown in Fig. 1.

Fig. 7 shows another manner of connecting the suspenders to the thigh member. As shown, this member is provided with two buttons 78 at its front upper portion. The cord 80 is provided at its forward end with an eye 84 adapted to be placed over the inner button 78. The cord then passes through a loop 94 secured to the top of the thigh member and the loop 96 secured lower down at the outer side of the thigh member and then after passing through a loop on the rear of the thigh member corresponding to the loop 94, has its free end attached to a loop or other securing device 98 on the rear inner side of the thigh member. The loop 94 may be secured by means of one of the buttons 78 so that the latter may have the double function of securing said loop and also serving as an attachment for the suspenders when they are attached directly to the buttons 78. A pair of suspenders 100 have their lower front ends provided with a series of openings 102 adapted to be engaged by buckles 104 which are attached to the two ends of a loop member 106 through 130

which the front portion of the cord 80 passes. The lower rear ends of the suspenders are united to form a loop 108 through which the rear portion of the cord 80 passes.

5 In case this cord should break the front ends of the suspenders may be attached to the two buttons 78 by means of openings therein while the rear portion of the suspenders may be tied to a loop 110 secured to the 10 rear upper portion of the thigh member. In this manner a temporary attachment of the suspenders to the thigh may be made without the provision of the buttons on the rear of the thigh member where they would 15 be objectionable, particularly when the wearer is seated. The construction shown in Figs. 8, 9, and 10 provides a desirable arrangement of joint for the shank member. The two overlapping edges of the joint are 20 broadened out toward the lower reduced portion of the shank to form the portions 112 and 114 so that substantially the rear one-half of the shank at the lower end is of double thickness. The material from which 25 the shank member is formed may be conveniently shaped to form this joint when the shell member is being formed. If desired a metal reinforcing strip 116 corresponding to the overlapped portion of the shell may be 30 secured on the inside in any suitable manner. This joint provides a very strong construction at the place where the shank is most liable to break. The joint may be secured together by a double row of rivets or 35 other fasteners 118 extending the full length of the shank and an extra row of rivets or other fasteners 120 at each side where the overlapping edges broaden out.

Fig. 11 shows a desirable form of ankle 40 joint construction. To the cylinder member of joint 17 are secured a pair of bolts 122 which extend up through the block 124 secured in the lower end of the shank member and the upper ends of these bolts are 45 provided with nuts 126 which may be locked by a spring member secured between them. The trunnion member which turns in the cylindrical member is provided with a single bolt 128 which extends down through the 50 foot member 16 and has a nut 130 screwed on the lower end thereof. The lower side of the foot member is provided with a recess which receives a plate 132 of metal or other durable material through which extend the bolt 128 and two other bolts 134 and 136 55 provided with nuts 138 and 140 respectively which in connection with the nut on the end of the bolt 128 may be locked by one or more spring members 142. The rear bolt 60 136 has a hooked upper end to which is attached a cord 144 the upper end of which is secured to a bolt 146. The front bolt 134 has a hooked upper end to which is attached spring 148, the upper end of which is attached to the bolt 146. The upper side of 65

the foot member may be provided with a buffer 150 to engage the block 124. Fig. 12 shows a construction of angle joint which does not have a block in the lower end of the shank member. The fixed 70 member of the ankle joint is secured to metal strips 152 on the inside of the shank member and the rotatable member of the ankle joint is provided with a bolt 153 which extends down through the plate 132 75 and is provided with a nut 154. Two bolts 156 and 158 extending through the plate 132 are provided with nuts 160 and 162 respectively which, in connection with the nut 154, may be locked by one or more 80 spring members 164. To the upper end of the rear bolt 158 is attached a cord 168, the upper end of which is attached to the bolt 170. To the upper end of the front bolt 156 is attached an elastic member 172 85 the upper end of which is attached to the bolt 170. The intermediate portion of the bolt 170 may be provided with an enlargement 171 to keep the members 168 and 172 from sliding out of position. The front 90 lower portion of the shank is provided with a plate 174 of metal or other durable material secured thereto. The lower end of this plate is provided with a lug or projection 176 with which the buffer 178 on the 95 top of the foot member or the foot member itself may engage when the front portion of the foot member swings upwardly.

I claim:

1. An artificial limb comprising a shank 100 member and a thigh member pivoted together to form a knee joint, an elastic member attached at its upper end to the knee joint portion of the thigh member and attached at its lower end to the rear portion 105 of the shank member below the top thereof, and means operable from outside said shank member for adjusting the tension of said elastic member.

2. An artificial limb comprising a shank 110 member and a thigh member pivoted together to form a knee joint, an elastic member attached at its upper end to the knee joint portion of the thigh member, a bar movably mounted within the rear portion 115 of the shank member, the lower end of said elastic member being attached to said bar, and means for holding said bar in different positions whereby the tension of said elastic member may be varied. 120

3. An artificial limb comprising a shank member and a thigh member pivoted together to form a knee joint, an elastic member attached at its upper end to the knee joint portion of the thigh member, a bar 125 slidably mounted within the rear portion of the shank member, the lower end of said elastic member being attached to said bar and a cam engaging a lug on said bar and rotatably mounted upon the shank 130

member whereby the tension of said elastic member may be varied.

4. An artificial limb comprising a shank member and a thigh member pivoted together to form a knee joint, a coil spring attached at its upper end to a knee block in the lower end of said thigh member, a bar slidably mounted within the rear portion of said shank member, the lower end of said 10 spring being attached to said bar, a cam engaging a lug on said bar and rotatably mounted upon the shank member, and means whereby said cam may be turned from the outside of the shank member to vary the tension of said spring.

5. An artificial limb comprising a hollow shell formed from a sheet of fiber, the longitudinal edges of which are brought together to form an overlapping joint, and a 20 strip of durable material secured to both of said overlapping edges to strengthen the joint, said material having a breaking characteristic which is different from that of the fiber.

25 6. An artificial limb comprising a shank member and a thigh member pivoted together to form a knee joint, a pair of suspenders for holding the thigh member to the wearer, a cord to which the lower ends of 30 said suspenders are slidably attached, a guide on the outer side of said thigh member under which the intermediate portion of said cord passes, loops attached to said thigh member adjacent said guide and through 35 which the respective front and rear portions of said cord pass, and fasteners on the front and rear inner portions of said thigh member to which the respective free ends of said cord are attached.

40 7. An artificial limb comprising a shank member and a thigh member pivoted together to form a knee joint, a pair of suspenders for holding the thigh member to the wearer, a cord to which the lower ends of 45 said suspenders are slidably attached, a guide on the outer side of said thigh member under which the intermediate portion of said cord passes, loops attached to said thigh member adjacent said guide and through which the 50 respective front and rear portions of said cord pass, fasteners on the front portion of said thigh member, a free end of said cord being attached to one of said fasteners, the lower front ends of said suspenders being 55 provided with holes adapted to be engaged over said fasteners when desired, a fastener on the rear portion of said thigh member to which the other free end of said cord is attached, and a loop on the rear portion of said 60 thigh member to which the lower rear ends of said suspenders may be secured when desired.

8. An artificial limb comprising a shank

member and a thigh member pivoted together to form a knee joint, an elastic member attached at its upper end to the knee joint portion of the thigh member, a bar slidably mounted within the rear portion of the shank member, the lower end of said elastic member being attached to said bar, a cam engaging a lug on the lower end of said bar and rotatably mounted upon the shank member whereby the tension of said elastic member may be varied, said cam having a plurality of spaced peripheral recesses and a spring 75 attached to said lug and provided with a projection adapted to engage with any one of said recesses.

9. An artificial limb comprising a hollow shank member having overlapping edges at 80 the rear thereof, said edges being broadened out at the lower reduced portion of said shank member to form substantially the rear half at the lower end thereof of double thickness, and means for securing said edges together.

10. An artificial limb comprising a hollow shank member having overlapping edges at the rear thereof, said edges being broadened out at the lower reduced portion of said 90 shank member to form substantially the rear half at the lower end thereof of double thickness, a reinforcing strip on the inside of said shank member having a width substantially the same as the overlapped portion 95 of said shank member and means for securing said edges and said strip together.

11. An artificial limb comprising a hollow shank member, a plate of durable material secured within the lower front portion of 100 said shank member, a lug on the lower end of said plate and a foot member pivoted to said shank member and adapted to engage said lug.

12. An artificial limb comprising a thigh 105 member, a pair of suspenders for holding said member to the wearer, and connections between said thigh member and suspenders for adjusting movement of the latter whereby movement of said connections is controlled entirely at the outer side of said thigh member.

13. An artificial limb comprising a thigh member, a pair of suspenders for holding said member to the wearer, a cord to which 115 the lower ends of said suspenders are slidably attached, a guide on the outer side of said thigh member for the intermediate portion of said cord, and means for fastening the free ends of said cord respectively to the 120 front and rear inner portions of said thigh member.

In testimony whereof I hereunto affix my signature.

OSCAR E. WORMAN.
